CLAIM

The ornamental design for a television receiver, as shown and described.

DESCRIPTION

FIG. 1 is a front perspective view of a television receiver showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a rear perspective view thereof; and,

FIG. 9 is an enlarged front perspective view of the portion encircled in FIG. 1.

The dashed broken lines in the figures illustrate portions of the television receiver that form no part of the claimed design.

The dot-dash broken lines encircle a portion of the claimed design that is illustrated in an enlargement and form no part of the claimed design.

1 Claim, 8 Drawing Sheets(56)
